UNITED STATES PATENT OFFICE.

CHARLES O. REEPS, OF CHICAGO, ILLINOIS.

LAUNDRY PRICE CHART.

Application filed June 5, 1922. Serial No. 565,888.

To all whom it may concern:

Be it known that I, CHARLES O. REEPS, a citizen of the United States, residing at Chicago, in the county of Cook and State 5 of Illinois, have invented certain new and useful Improvements in Laundry Price Charts, of which the following is a specification.

The average laundry work of the average 10 family consists of approximately equal weights of flat work, such as table linen, bed linen, towels, etc., and wearing apparel.

The equipment facilities for a public laundry, that is to say the types and styles 15 and capacities of the machines and their operators employed for doing its work should be such that they will be proportioned or adapted to perform laundry work on the ratio of flat work to wearing apparel

20 of the average family as indicated above.

If, therefore, a bundle of laundry work is received, especially in a laundry where the contents of the individual parcels are at all times maintained separate from those of

25 other bundles, which varies substantially from the proportion indicated, the laundry establishment will not be working at maximum efficiency, when performing that particular service, and, accordingly, a somewhat 30 greater price or service charge is warranted under such circumstances to compensate for the disproportion of the two kinds of articles to be cleaned.

For example, the keeper of a lodging 35 house is likely to send to the laundry an excessive amount of flat pieces as compared with the articles of wearing apparel and the machines and employees for handling the latter must necessarily be idle for a portion of the time while the other work is being performed.

On the other hand, a family with a relatively large number of children is likely to have an unduly large proportion of articles 45 of wearing apparel, necessitating an idleness of the flat work equipment for a part of the time.

Accordingly, both the rooming house keeper and the family with the number of 50 children ought to be charged relatively more

for such laundry work than the family which sends in flat work and wearing articles in the normal ratio which is proportioned to the equipment of the laundry, thereby being a direct factor in the maintenance of the efficiency of operation of the laundry establishment.

It is of advantage both to the housewife and to the owner of the laundry plant if the bundles of work can be maintained 60 with their contents in something like the ratio specified.

To the end, therefore, of encouraging the housewife to forward laundry with flat pieces and clothing substantially in the normal proportion, I have invented a simple 65 price chart which aims to indicate the advantages accruing from approximating such ratio.

Therefore, in the accompanying drawing, 70 forming a part of this specification, I have illustrated a fragment of such novel price chart representing a desirable and preferred embodiment of the invention.

Referring to such drawing, it will be perceived that it consists of vertical rows of price amounts, the latter being arranged also in horizontal rows.

At the tops of these vertical columns, 75 there are displayed the progressive or numerically successive weights in pounds of flat work, and at the left-hand edge of the chart there is an upright column of figures representing the different weights in pounds of wearing apparel.

80 Stated somewhat differently, the chart is blocked off into rectangular sections in horizontal and vertical rows, the several sections across the top of the chart containing figures representing pounds of flat work, whereas the sections of the first vertical row display numbers corresponding to pounds of wearing apparel, the other sections having price marks indicating the total cost of the number of pounds of flat pieces denoted at the 85 top of the corresponding upright column plus the number of pounds of articles of clothing specified in the block at the left end of the same horizontal row.

90 The exact cost of the laundry work can 100

be easily predetermined before sending it out by weighing separately the flat pieces and the wearing apparel and then consulting the chart to ascertain the amount specified in that block thereof located at the intersection of the two rows corresponding to the weights of the two types of articles to be laundered.

For example, if there are seven pounds of flat pieces and twelve pounds of wearing pieces, the laundry service charge would be \$2.98.

By inspecting the chart or table, it will be perceived that there is a minimum charge of \$1.62, and for this amount laundry work up to five pounds of flat pieces and five pounds of wearing apparel can be sent, but the charge is not decreased if a lesser amount is forwarded.

This charge item is based on five pounds of flat work at sixteen cents per pound, five pounds of clothing or wearing apparel at sixteen cents per pound, and two cents for insurance.

For each pound of flat pieces above the minimum five pounds, a charge of six cents per pound is made, and, for each pound of wearing apparel in excess of the minimum five pounds, up to nine pounds, a charge of sixteen cents per pound is made but for and over nine pounds the increase is at the rate of twenty-two cents per pound.

The reason for this is that up to nine pounds the ironing of the wearing apparel may be done relatively efficiently, but the amount in excess of eight pounds dries out during the ironing of such eight pounds requiring sponging, partial drying and then ironing, thus necessitating extra time and labor on the part of the worker.

Referring to the table or chart again, in order to ascertain the maximum amount of flat pieces which may be sent without additional charge, it is merely necessary, knowing the pounds of wearing apparel, to follow horizontally along the corresponding row to find where the first price increase occurs and at the top of such column will be found the amount of flat pieces.

For instance, fourteen pounds of flat work can be sent with seventeen pounds of wearing apparel without extra charge, but for every pound above fourteen, the cost will be six cents per pound.

A chart of this character enables the housewife to economize in the cost of laundry work by sending, so to speak, "balanced" or "normal" or "average" bundles of laundry articles, the saving being rendered possible by reason of employing the laundry equipment under most advantageous conditions.

The invention is, of course, not limited to this particular chart or table, the details of which are subject to considerable modifica-

tion, the scope of the invention being defined by the appended claims including the usual range of equivalents.

I. claim:

1. A laundry price-chart of the character described, displaying price amounts arranged in horizontal rows and vertical columns, said rows and columns being designated with various amounts of different types of laundry articles respectively, each such price item representing the charge for the joint amounts of the two types of laundry corresponding to the row and column of which such item forms a part. 70

2. A laundry price-chart of the character described, displaying price amounts arranged in horizontal rows and vertical columns, said columns and rows being designated with various weights of flatwork and wearing apparel respectively, each such price item representing the charge for the joint weights of flat-work and wearing apparel corresponding to the column and row of which such item forms a part. 85

3. A laundry price-chart of the character described, displaying price amounts arranged in horizontal rows and vertical columns, said columns and rows being designated with progressive weights of flat-work and wearing apparel respectively, each such price item representing the charge for the joint weights of flat-work and wearing apparel corresponding to the column and row of which such item forms a part, the minimum price item being the same in a number 90 for such horizontal rows and vertical columns. 100

4. A laundry price-chart of the character described displaying price amounts arranged in vertical columns and horizontal rows designated with various weights of flat-work and wearing-apparel respectively, each such price item representing the charge for the joint weights of flat-work and wearing-apparel corresponding to the column and row of which such item forms a part, the price per pound of wearing-apparel increasing with an increase in the weight of such type of laundry work. 110 115

5. A laundry price-chart of the character described, displaying price amounts arranged in vertical columns and horizontal rows designated with various weights of flat-work and wearing-apparel respectively, each such price item representing the charge for the joint weights of flat-work and wearing-apparel corresponding to the column and row of which such item forms a part, the price per pound of wearing-apparel increasing with an increase in the weight of such type 120 of laundry work, the price per pound of flat-work decreasing with an increase in the weight of such style of laundry-work. 125

6. A laundry price-chart of the character described, displaying price amounts arranged 130

in vertical columns and horizontal rows designated with various weights of flat-work and wearing-apparel respectively, each such price item representing the charge for the joint weights of flat-work and wearing-apparel corresponding to the column and row of which such item forms a part, the price for any predetermined weight of wearing-apparel including a predetermined weight of flat-work before an increase in price, the 10 weights of flat-work thus included increasing with the increase of weight of wearing-apparel.

In witness whereof I have hereunto set my hand and seal.

CHARLES O. REEPS. [L. s.]
